UNITED STATES PATENT OFFICE.

EDWARD L. HURD, OF MILTON, MASSACHUSETTS, ASSIGNOR TO UNITED SHOE MACHINERY COMPANY, OF PATERSON, NEW JERSEY, A CORPORATION OF NEW JERSEY.

SOLE-ROUNDING MACHINE.

1,109,842.

Specification of Letters Patent. Patented Sept. 8, 1914.

Application filed March 2, 1912. Serial No. 681,144.

To all whom it may concern:

Be it known that I, EDWARD L. HURD, a citizen of the United States, residing at Milton, in the county of Norfolk and State of Massachusetts, have invented certain new and useful Improvements in Sole-Rounding Machines; and I do hereby declare the following to be a full, clear, and exact description of the invention, such as will enable others skilled in the art to which it appertains to make and use the same.

This invention relates to sole rounding machines of that general type employing a pattern of the shape of the sole to be rounded, a knife carrier, and means for relatively moving the pattern and knife carrier to transfer the point of operation of the knife around the sole.

When operating upon McKay soles, it is usual to provide a machine of this character with a channeling and a grooving knife. The channel is cut from a point just back of the breast line around the shank and fore part to a point opposite the starting point. It is usual to commence the rounding operation near the heel and round the heel end of the sole first. When the opposite side of the heel is reached, the channel knives are thrown into operation. On the completion of the operation the channel knives are withdrawn at about the point where the rounding cut was commenced. It is common to allow the rounding knife to travel more than a complete revolution of the sole; that is, to overrun the commencement of the cut in order to insure the complete severance of the waste material from the sole.

In the operation of the rounding machines now in use, the knife comes to rest after the sole is rounded, with its blade pressed against the pattern. The sole blank is then placed upon the pattern with one point on its edge coincident with the edge of the pattern and against the knife. When so placed, every other part of the periphery of the sole should project beyond the pattern. If the contour of the sole blank is such that another point than that at the knife does not project beyond the pattern, the stopping position of the knife is adjusted along the pattern until the margin of the sole blank projects beyond the pattern at every point except where it engages the knife. There

is no objection to such an adjustment of the knife if no channel is being cut in the sole. It is necessary, however, when a channeling knife is employed, to start the rounding and channeling operations in the vicinity of the breast line.

One object of the present invention is to provide a sole rounding machine which will come to rest with the knife out of contact with the pattern so that there will be no necessity of placing any portion of the edge of the sole blank in coincidence with the edge of the pattern.

In accordance with this object, one feature of the invention comprises means in a sole rounding machine for moving the rounding knife away from the pattern after the completion of the rounding operation. In the illustrated embodiment of the invention such movement occurs during the travel of the knife from its stopping point back to the point where the cut on the succeeding sole will be commenced. Broadly considered, however, this feature of the invention is not limited to use in a machine in which the knife is caused to overrun the starting point of the cut.

Another objection which has been observed in the usual manner of positioning the sole on the pattern is that the blade of the knife, when in position to start a cut, is parallel to or sometimes so turned that the cutting edge of the knife is inclined away from the sole edge. It is often necessary, in order to cause the knife to properly start the cut, for the operative to cut a slight notch in the sole by forcing it against the knife by hand and thus cause an engagement of the knife edge with the sole edge before it is clamped upon the pattern.

Another object of this invention is to overcome this difficulty by providing in a sole rounding machine, means for positioning the rounding knife with its cutting edge inclined toward the sole edge before the rounding operation is commenced.

To this end, a further feature of the invention comprises means for bringing the rounding knife into a position with its cutting edge directed diagonally toward the sole edge before the rounding operation is commenced. It has been found convenient to turn the rounding knife into this position.

at the same time that it is removed from contact with the pattern as heretofore described, although this feature of the invention is not limited in its use to a sole rounding machine in which the knife overruns the point of completion of the cut.

Another object of the invention is to provide means in a sole rounding machine for operation upon McKay or other soles in which the channel is cut during the rounding operation, for varying the distance of the channel cut from the edge of the sole while using the same patterns which are employed for soles without a channel.

In accordance with this object a further feature of the invention comprises the provision of an auxiliary pattern, coöperating with the usual pattern, conforming in shape to the contour of the channel to be formed.

Means is provided for guiding the rounded knife in the usual manner by its pattern while the channel knife is positioned by the auxiliary pattern which would, ordinarily, be narrower in the shank.

Another object of the invention is to provide improved means in a sole rounding machine for automatically withdrawing the channeling knife from the sole at the end of the cut.

In accordance with this object, a further feature of the invention comprises the provision in a sole rounding machine, of a lever carried by the channeling knife block, and means for actuating the lever at the end of the cut, to engage the sole and lift the channeling knife therefrom.

To the accomplishment of these objects, and such others as may hereinafter appear, the invention comprises the general features and combinations of parts hereinafter described and more particularly pointed out in the appended claims.

The invention is illustrated as embodied in a machine of the general type disclosed in Letters Patent of the United States, No. 911,511, dated February 2, 1909 and granted to United Shoe Machinery Company on the application of Mayo & Buckminster. It is to be understood, however, that the invention is not limited in its application to the particular type of sole rounding machine therein described and illustrated.

The preferred embodiment of the invention is illustrated in the accompanying drawings, in which:

Figure 1 is a front elevation of the upper portion of a sole rounding machine of the type referred to; Fig. 2 is a section on an enlarged scale on the line 2—2 of Fig. 1 showing the position of the rounding knife and associated parts in their normal position of rest at the completion of an operation upon a sole; Fig. 3 is a plan of the rounding knife and knife block; Fig. 4 is an elevation of the parts shown in Fig. 3 looking from

the left; Fig. 5 is an enlarged section on the line 5—5 of Fig. 1 showing the parts in the position occupied when operating upon the shank of a sole; Fig. 6 is an elevation showing particularly the channeling and 70 grooving knives and the means for withdrawing them from the sole at the completion of the cut; Fig. 7 is a detail view showing particularly the channel knife and its retaining means; Fig. 8 is a detail of the 75 tripping arm by which the mechanism for lifting the channeling and grooving knives is actuated.

The general mode of operation of the illustrated sole rounding machine is identical with that of the Mayo & Buckminster patent to which reference has been made and from which a full description of its actuating mechanism may be had. The mechanism for imparting the overrun or 85 excess travel of the rounding knife beyond its starting point may be such as is described in the Letters Patent of the United States, No. 540,062, granted upon the application of Gideon Julian and dated May 90 28, 1895 to which reference may be had for a complete description. The general mode of operation of machines constructed in accordance with the aforementioned 95 patents is well known in the art and therefore there is illustrated and particularly described herein only those parts of the machine closely associated with the knives and embodying the novel features of the invention. There is indicated in Fig. 1 the arm 100 1 carrying the usual clamping devices for securing the sole upon the rounding pattern R which is mounted upon the table 2. The knife holder arm 3 is of the usual construction and adapted to hold the cutting tools 105 yielding toward the pattern. All of these parts may be, and preferably are, in accordance with the patents hereinbefore referred to.

A knife carrier or yoke 4 is secured by 110 trunnions 5 to the end of the arm 3. The lower arm of the yoke (Fig. 5) has fixed thereon a block 6 which is yieldingly pressed by the arm 3 against an auxiliary or channeling pattern C. The rounding knife block 115 8 is mounted upon the block 6 so as to slide toward and from the pattern R. Its forward motion is limited by a pin 9 toward which the block is pressed by a spring 10 (Figs. 3 and 5). The rounding knife 11 is 120 clamped in a slot in the knife block by a screw 12. The front or inner end of the rounding knife block is adapted to engage the rounding pattern R as is usual in machines of this character. It is apparent 125 from Fig. 5 that the block 6 will cause the knife carrier 4 to move in and out in accordance with the contour of the channeling pattern C, but the knife block 8, being spring pressed against the rounding pat- 330

tern R by a spring of considerably less strength than the spring which holds the knife carrier toward the patterns, will move in and out in accordance with the contour of the pattern R.

The yoke or knife carrier 4 carries a block 14 (Figs. 5 and 7) adjustably secured thereon by a screw 15. A second block 16 is mounted on the block 14 and adapted to swing about a pivot 17 to move the channeling and grooving tools carried thereby toward and from the work. The front end of the block 16 has an adjustably mounted presser foot 18 (Fig. 6) which, during the channeling operation, bears upon the sole and determines the depth of the channel made therein. A grooving tool 19 is adjustably secured to the block 16 by a screw 20 passing through a slot in a strap 21 (see Fig. 5). The lower end of the strap is rounded and engages a groove in the shank of the grooving tool and its upper end is slotted to receive a collar on a screw 22 threaded into the block 16. By loosening the screw 20, the knife may be adjusted vertically by the screw 22 and longitudinally by hand. The block 16 also carries the channel knife 23 (Figs. 6 and 7) mounted thereon in such a manner that it may be replaced after grinding in its original position. The channel knife is secured to the block by means of a strap 24 which may be clamped in adjusted position by the screw 25. The lower end of the strap 24 is rounded and engages a groove in the shank of the channel knife and its upper end engages a groove 26 in the block 16 which is on an arc struck from the center of the screw 25. The strap 24 is connected by a pin 26 with one end of a link 27, the other end of which is slotted to receive a screw 28 threaded into the block 16. When the screw 25 is loosened, the channel knife 23 may be withdrawn for sharpening and replaced at its original angle. If it is desired to adjust the angle of the channel knife, the screw 28 must be loosened as well as the screw 25 to permit the strap 24 to be swung about the screw 25 as a center. If the screw 28 is then made tight, the angle of the strap 24 will be fixed so that the knife may be withdrawn and replaced as often as desired without losing its angular location. A stop screw 29 is threaded into the block 16 to provide an adjustable abutment for the channel knife 23 in order that it may be replaced after sharpening in its original longitudinal position. The block 16 may be swung about the pivot 17 to lift the knives carried thereby from the work by means of the handle 30 pivoted on the block 16 and having a cam surface 31 in contact with the block 14. A spring 32 is interposed between the lug 33 on the block 16 and a set screw 34 mounted in the block 14

to yieldingly hold the block 16 and its knives toward the sole.

Referring now more particularly to Fig. 6, the feature of the invention which relates to the automatic lifting of the channeling and grooving knives at the completion of the cutting operation comprises two levers 36 and 37 pivoted one above the other on a part of the presser foot 18. The lower lever 37 is adapted to be actuated upon a movement of the upper lever by means of a lug 38 engaging a corresponding slot in the lever 37. This is, in effect, a single toothed gear. The position of these levers during the channeling and grooving operations is shown in full lines in Fig. 6, at which time the lower end of the lever 37 is swung about its pivot into a position above the sole and above the sole engaging portion of the presser foot 18. At this time the lug 38 forms a lock to prevent accidental movement of the lever 37. The lever 36 is normally held in the position shown in Fig. 3 by a torsion spring 39 (Fig. 5) which holds its finger 40 against a portion of the lever 37. At the time when the channeling and grooving knives are to be withdrawn from the sole, the upper end of the lever 36 engages a yielding abutment formed by an arm 41 projecting from the standard 42 which is of a construction common to machines of this character. Fig. 5 illustrates the knife lifting mechanism at the point in the channeling operation when it is about to be actuated by the arm 41 and be turned into the position shown in dotted lines in Fig. 6. The lever 37 at this time acts, by reason of its engagement with the sole, to pry the tools from the sole and to hold them in their raised position so long as the lever 37 continues to bear upon the sole.

The mounting of the arm 41 is shown particularly in Figs. 5 and 8. The arm 41 is pivoted at 43 in a stud 44 which is adjustably secured in the head of a bolt 45. The bolt 45 is held yieldingly downward by a spring 46 which holds the stud at the bottom of a V-notch 47 formed in a bearing 48 secured to the standard 42. This arrangement provides a yielding abutment, for engagement by the lever 36, which will be returned to its normal position upon the removal of the pressure by the lever. Describing the operation of these parts more particularly, at the completion of the rounding and channeling operation the lever 36 engages the arm 41 and is thereby moved backwardly (to the right in Fig. 6) without ordinarily changing the position of the stud 44 in its notch 47 because the spring 46, holding the pin in the notch, is stronger than the spring 39 acting on the lever. The spring 46, however, permits the stud 44 to yield, if occasion requires. This turns the lever 37 down into engagement with the sole and

lifts the channeling and grooving knives. Continued pressure on the arm 41, caused by the continued forward movement of the knife carrier for the over-run after the channeling and grooving knives have been lifted from the sole, lifts it upward, the arm turning about its pivot 43, and, if the over-run is sufficiently long, permits the lever 36 to pass beneath it. The arm 41 thus offers no obstruction to the over-run movement of the rounding knife. Similarly on the return of the knife carrier, after over-running, the lever 36 which has dropped to the full line position of Fig. 6 again lifts the arm 41 about its pivot 43 and passes beneath it to the position shown in Fig. 2.

After the machine has come to rest and preferably before the removal of the rounded sole, the operative will lift the lever 30 into a horizontal position (see Fig. 1) to raise the block 16 and thus to remove the channeling and grooving knives, presser foot and the automatic means for lifting these parts, from engagement with the sole. The parts remain in this position when the operation upon the next sole is commenced and continue in this inoperative position until the tools reach the point at which it is desired to commence the channeling operation. This point is designated by *a* on Fig. 2. Mechanism (see Figs. 1 and 2) is provided for automatically depressing the handle 30 and rendering the channeling tools operative at this time. The arm 3 carries a bell crank lever 49 pivoted on a stud 50 and normally held with the arm 51 in a substantially vertical position by means of a spring 52. When the lever 30 is in a horizontal position, that is, when the channeling tools are inoperative, the handle lies below the arm 53 of the bell crank. The other arm 51 will strike an adjustable finger 54 at the time the channeling is to be commenced, thus turning the bell crank and depressing the handle 30, which will lower the channeling and grooving knives into their operative positions.

The finger 54 is adjustably mounted in a bracket 55 pivoted at 56 on a projection from the standard 42. The bracket 55 is held in its normal position by a spring pressed plunger 57 in engagement with a flat boss on the bearing projecting from the standard 42. If it is desired to render the finger inoperative, it may be lifted and will be held in the raised position by the flattened boss 58 (Fig. 2). Such slight variation as may be desired in the position of the stop and start of the channel and groove may be obtained by moving the standard 42 in the bracket 59 and adjusting the finger 54. This standard and the similar standard for the toe end of the sole are secured by winged nuts 60 in the bracket 59 in the usual manner.

65 The mechanism provided for moving the

rounding knife away from the pattern and at the same time turning it so that its cutting edge points diagonally toward the pattern, is shown particularly in Figs. 1 and 2. The backward motion of the cutting tools on the return after the over-run or excess travel in rounding the sole is shown in Fig. 2 as being from the point indicated approximately by *b* to the position of the tools in that figure. The knife carrier 4 has a vertical pin 62 which, during the backward movement of the tools, will engage a latch 63. The location of the pin is such that contact with the latch will turn the knife carrier 4 and, therefore, all the tools carried thereby, about the trunnions 5. The form of the rounding knife block is such that the rounded forward end acts as a lever to pry the rounding knife away from the pattern (see Fig. 3). The turning of the rounding knife block about its corner will leave the rounding knife with its cutting edge directed diagonally toward the pattern when the machine comes to rest, as indicated in dotted lines in Fig. 2.

90 The latch 63 is pivoted on the lower end of a hinged bracket 64 which is adjustably secured to the arm 1 by a screw 65. A lug 66 on the bracket engages a lug 67 on the latch to limit the downward motion of the latch 95 and hold it normally in the position shown in Fig. 1. Thus when the pin 62, during the forward movement of the tools, passes beneath the latch, it will be lifted to allow the pin 62 to pass and then drop and rotate the 100 knife carrier 4 upon movement of the carrier and cutting tools in the reverse direction. By loosening the screw 65, the bracket 64 may be adjusted to give the rounding knife the desired angle and amount of withdrawal from the pattern. The bracket 64 is hinged and adapted to be held either in its operating position or in a horizontal position by a spring plunger 69 in order that it may be lifted to allow convenient access to 110 parts beneath it.

115 In the operation of this machine the sole blank is placed upon the pattern R while the machine is at rest with the moving parts in the position shown in Fig. 2, with the handle 30 raised. As thus located the margin of the sole projects from the pattern around its entire periphery. The operator will then depress the treadle, which will clamp the sole upon the pattern and start the operation 120 of the machine in the usual manner. The rounding knife at this time is in such a position that its cutting edge is directed at an angle toward the sole and, therefore, it cannot fail to immediately take a chip and it 125 will rapidly run in toward the pattern, under the influence of the knife holder arm spring, until the knife block contacts therewith. The knife block will then follow the contour of the rounding pattern around the 130

heel in the direction of the arrow of Fig. 2, and as the bell crank 49 passes below the finger 54, it will be actuated in the manner described to throw the channeling and 5 grooving knives into operation at *a* (Fig. 2). The channeling tool will follow the contour of the channeling pattern C, as indicated in dotted lines in Fig. 2, thus producing a wider margin outside the channel at 10 the shank of the sole than at the commencement of the cut at the heel or around the forepart. After passing around the forepart and the other side of the shank, the tools operate to a point indicated on the 15 pattern in Fig. 2 at *b*, which is somewhat beyond the starting point, at which time the forward movement of the tools is stopped and a slight movement in the reverse direction takes place. Just before the tools stop 20 their forward motion, the arm 41 engages the trip lever 36 which actuates the lever 37 to pry the channeling and grooving knives from the sole in the manner described. The reverse movement turns the rounding knife 25 in the manner which has been described and the machine is brought to rest. The operator will then lift the handle 30 to remove the lever 37 from contact with the sole and remove the sole which has been rounded. It is 30 evident that if it is desired to vary the width of the margin or feather at the shank, this can be done by inserting a channeling pattern of different configuration.

While the specific construction and arrangement of parts shown and described in the drawing is the best form at present known to the inventor, it should be understood that this construction and arrangement is not essential except in so far as 40 specified in the claims.

What is claimed as new, is:—

1. A sole rounding machine, having, in combination, a pattern, a rounding knife guided by the pattern, means for imparting 45 a relative movement to the pattern and the rounding knife to round the sole, and means operating at the end of the rounding operation for swinging the knife away from the pattern to a position with its cutting 50 edge directed diagonally toward the pattern, substantially as described.

2. A sole rounding machine, having, in combination, a pattern, a rounding knife guided by the pattern, means for imparting 55 a relative movement to the pattern and the rounding knife to round the sole, and means operating automatically at the end of the rounding operation for moving the knife out of contact with the pattern, substantially 60 as described.

3. A sole rounding machine, having, in combination, a pattern smaller than the sole blank to be operated upon, a rounding knife guided by the pattern, means for imparting 65 a relative movement to the pattern and the

rounding knife to round the sole, and means for initially holding the rounding knife in such a position that the cut on the sole is commenced at the edge of the margin projecting from the pattern and continues 70 diagonally toward the pattern until the pattern is reached, substantially as described.

4. A sole rounding machine, having, in combination, a rounding knife guided by the pattern, means to cause the knife to traverse 75 the outline of the pattern, overrun and return to its starting point, and means operating during the return movement to swing the rounding knife to a position with its cutting edge pointing toward the sole and its 80 blade directed at an acute angle to the outline of the pattern, substantially as described.

5. A sole rounding machine, having, in combination, a rounding knife and a channeling knife, a pattern for guiding the rounding knife, a block for supporting the channeling knife, means to cause the rounding knife to traverse the outline of the pattern, a pair of geared levers pivotally 85 mounted on the channeling knife block, one of said levers being arranged to engage the sole and means for automatically actuating the other lever to pry the channeling knife out of operative engagement with the 90 sole at the end of the traversing movement of the rounding knife, substantially as described.

6. A sole rounding machine, having, in combination, a rounding knife and a channeling knife, a pattern for guiding the rounding knife, a block for supporting the channeling knife, means to cause the rounding knife to traverse the outline of the pattern, a lever pivoted on the knife block and movable to engage the sole and pry the channeling knife out of operative engagement therewith and means for automatically actuating said lever at a predetermined point 105 in the rounding operation, substantially as 110 described.

7. A sole rounding machine, having, in combination, a rounding knife, a pattern for guiding the rounding knife, channeling devices, a separable pattern of different outline for guiding the channeling devices, and means for imparting movement to the tools to cause them to traverse the outlines of their respective patterns, substantially as 115 described.

8. A sole rounding machine, having, in combination, a rounding knife and a channeling knife, a pattern for guiding the rounding knife, means to cause the rounding knife to traverse the outline of the pattern and to overrun the starting point, resilient means for maintaining the channeling knife in engagement with the sole, and means to engage the surface of the sole and operate automatically during the overrun 120 125 130

movement of the rounding knife to raise the channeling knife out of engagement with the sole, substantially as described.

9. A sole rounding machine, having, in combination, a rounding knife and a channeling knife, a pattern for guiding the rounding knife, means to cause the rounding knife to traverse the outline of the pattern, resilient means for maintaining the channeling knife in engagement with the sole, and means to engage the surface of the sole and operate automatically to raise the channeling knife out of engagement with the work, substantially as described.
10. A sole rounding machine, having, in combination, a fixed pattern, means for clamping a sole blank on the upper surface of the pattern, a knife-carrier movable about the periphery of the pattern, a rounding knife carried by the knife-carrier and guided by the edge of the pattern, means for moving the knife-carrier about the pattern to cause the rounding knife to traverse the periphery of the pattern and overrun its starting point, a channeling knife carried by the knife-carrier and normally yieldingly engaging the sole, a lever carried by the knife-carrier and adapted to engage the upper surface of the work and hold the channeling knife out of engagement therewith, and a yielding trip device located in position to operate the lever and raise the channeling knife from the sole during the overrun movement of the rounding knife, substantially as described.

11. A sole rounding machine, having, in combination, a knife block, a channeling knife provided with a longitudinally grooved shank, a strap pivoted to the knife block and having a tongue engaging the groove in said shank, and a link pivoted to the strap at one end and adjustably secured at the other end to the knife block, whereby the strap is maintained in adjusted angular position when the channeling knife is removed from the knife block, substantially as described.

12. A sole rounding machine, having, in combination, a knife carrier, a rounding knife and a channeling knife mounted upon the knife-carrier with provision for independent movement and two superposed sep-

arately removable patterns having different peripheral outline for guiding the two knives respectively whereby the relation of the outline of the channel cut, to the edge of the sole, may be varied on soles having the same outline, substantially as described.

13. A sole rounding machine, having, in combination, a rounding knife, a rounding pattern for guiding the knife, channeling tools, a channeling pattern for guiding the tools, a block carrying the channeling tools, a lever on the block normally out of contact with the sole and a yielding abutment to actuate the lever and cause it to engage the sole and pry the channeling tools therefrom, substantially as described.

14. A machine for rounding soles the edges of which project at all points beyond the desired contour line, having, in combination, a knife for trimming the sole to the desired contour and automatic means for preliminarily positioning said knife with its cutting edge inclined to the sole edge whereby to effect an initial cut from the edge of the sole to the contour line, substantially as described.

15. A machine for rounding soles, having in combination, an edge trimming knife arranged to move along the line of cut, and means for operating said knife constructed to automatically position it so as to make its initial cut at an angle to the path in which it travels in continuing the cut, substantially as described.

16. A machine for rounding soles, having in combination, a trimming knife, a knife carrier therefor, and means for imparting a relative movement of translation to the sole and knife for trimming the sole along such line of movement, said means having provision for automatically swinging the knife carrier at the end of the rounding operation to a position in which the cutting edge of the knife is directed diagonally toward the sole edge whereby to effect the initial cut of the succeeding rounding operation at an angle to the main line of the cut, substantially as described.
